UNITED STATES PATENT OFFICE.

JOHN F. HUNHOLZ, OF WAMEGO, KANSAS.

BOW-GUN.

1,192,639.

Specification of Letters Patent. Patented July 25, 1916.

Application filed February 1, 1916. Serial No. 75,571.

To all whom it may concern:

Be it known that I, JOHN F. HUNHOLZ, a citizen of the United States, residing at Wamego, in the county of Pottawatomie, State of Kansas, have invented certain new and useful Improvements in Bow-Guns; and I do hereby declare the following to be a full, clear, and exact description of the invention, such as will enable others skilled in the art to which it appertains to make and use the same.

This invention relates to improvements in guns, and particularly to toy guns.

One object of the present invention is to provide a gun for projecting darts therefrom.

Another object is to provide a gun which combines the features of a bow.

Another object is to provide a device of this character which includes novel means for releasing the thong or cord of the bow.

Other objects and advantages will be apparent from the following description when taken in connection with the accompanying drawing.

In the drawing: Figure 1 is a side elevation of a bow gun made in accordance with my invention; Fig. 2 is a top plan view; Fig. 3 is a longitudinal sectional view on the line 3-3 of Fig. 2; and Fig. 4 is a section on the same line, but only through the trigger mechanism showing the said mechanism in the act of releasing the cord from the notch.

Referring particularly to the accompanying drawing, 10 represents an elongated piece of material, preferably wood having a longitudinal groove 11 in its upper edge. Adjacent one end of this member there is formed an opening 12. At the other end of the member 10 there is formed a vertical groove 13 opening respectively through the upper and lower edges of the said member. In the upper portion of this groove, and mounted on a transverse pivot 14 is a releasing finger 15, on the lower portion of which is formed a downwardly extending projection 16 arranged to be engaged by the upper end of the pivoted trigger 17. Rearwardly of the member 10 is a downwardly extending wooden member 18, the upper end of which bears against the rear end of the member 10 as shown at 19. The forward part of the upper end of the member 18 has secured therein a leaf spring 20, the free end of which bears on the releasing finger 15 to depress the same below the upper surface of

the member 10. Secured on each side of the members 10 and 18, and serving to secure said members together are two metal plates 21, the whole structure when thus secured together resembling a pistol. In the forward ends of the metal plates 21 are openings 22 registering with the opening 12 and through these openings is disposed a strip of flexible material 23 forming the bow. To the ends 65 of this strip are secured the ends of a cord 24. The intermediate portion of this cord is adapted to be drawn back and engaged in the notch 25 formed above the releasing finger 15 and in the member 10 as well as in 70 the members 21.

Disposed above, and extending the length of the gun, is an inverted semi-cylindrical member 26 which in connection with the groove of the member 10, forms the barrel 75 of the gun. At each end of the member 26 there are formed a pair of depending ears 27 which straddle the gun and are secured to the sides thereof. This member 26 is spaced above the gun a sufficient distance 80 to permit the cord to slide the length thereof. At a point above the notch 25 the member 26 is formed with notches 28 to permit the cord to move upwardly when released by the finger 15. In the member 26, just in 85 advance of the notches 28 there is formed a transverse wall 29 which prevents rearward movement of the dart past the proper point to be engaged by the cord.

The spring 20 normally forces the releasing finger 15 forwardly and below the bottom of the notch and at the same time the projection 16 engages the upper end of the trigger so as to rock the same and present the lower portion thereof at a forward and 90 downward inclination. Assuming the middle of the cord to be engaged in the notch 25, a dart is placed in the groove 11 and in the semi-cylindrical member 26 so that its rear end is just in advance of the notch 25 and rests against the wall 29. Upon pulling rearwardly on the trigger the finger 15 will be rocked on its pivot against the tension of the spring 20 so that its upper portion will 95 swing upwardly and rearwardly. This 100 pushes the cord upwardly and rearwardly out of engagement with the notch, and by the resiliency of the bow, the cord is jerked forwardly so as to strike the portion of the rear end of the dart below the wall 29 and 105 project the same through the groove 11 and away from the gun. It will be noted that 110

the notch 25 inclines downwardly and forwardly, and therefore there is required an upward and rearward movement of the finger 15 to disengage the cord from the notch. 5 The above-named action is accomplished by the peculiar curvature of the upper portion of the finger.

What is claimed is:

1. A bow gun comprising a pair of strips 10 of suitable material, a filler disposed between and secured to the strips, said filler consisting of two portions, the abutting faces of which are formed with grooves, one of the filler members and the strips having 15 alining notches, a bow stick disposed through the strips and filler, a cord connecting the ends of the bow stick and adapted to be engaged in the said notches, a trigger member pivotally mounted in the lower end of the 20 groove of one filler member and a pivoted releasing member mounted in the groove above the trigger and having a depending portion for engagement by the trigger, said releasing member having an upper eccentrically curved face for engagement with 25 and movement of the cord upwardly and rearwardly from the notches.

2. A bow gun comprising a pistol-shaped

body portion, a bow carried by the body portion and including a cord, an inverted semi-cylindrical member disposed in spaced relation above and secured to the barrel of the body portion, said inverted member and barrel portion having oppositely disposed notches, one of the notches being adapted 30 to receive the cord and a trigger mechanism including a finger movable upwardly and rearwardly to release the cord from one of the said notches.

3. A bow gun comprising a pistol-shaped 40 body, having a longitudinal groove and a notch, a bow carried by the body and including a cord for engagement in the notch, a trigger mechanism for releasing the cord and a housing secured to and spaced above 45 the body and coöperating with the grooved portion of the body to form a dart receiving barrel, and a stop wall carried by the inverted member above the said notch.

In testimony whereof I affix my signature, in the presence of two witnesses.

JOHN F. HUNHOLZ.
